CLAIM

The ornamental design for an interactive telecommunication station unit, as shown and described.

DESCRIPTION

FIG. 1 is a perspective view of an interactive telecommunication station unit showing our new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof; and,
FIG. 7 is a rear elevational view thereof.

The broken line structure in FIGS. 1-7 showing various elements and features of the interactive telecommunication station unit is for environmental purposes only and forms no part of the claimed design.

The broken line showing of the recess at the front right top of the article defines, but is not included in, the boundaries of the claimed configuration.
